F. Brumbauer INVENTOR

BY Munn & Co ATTYS

UNITED STATES PATENT OFFICE.

FERDINAND BRUNBAUER, OF VIENNA, AUSTRIA-HUNGARY.

INJECTOR.

SPECIFICATION forming part of Letters Patent No. 369,097, dated August 30, 1887.

Application filed March 29, 1887. Serial No. 232,923. (Model.) Patented in Germany July 3, 1885, No. 36,938; in France July 3, 1885, No. 169,922; in Belgium July 3, 1885, No. 69,475; in England July 3, 1885, No. 8,098; in Austria-Hungary August 3, 1885, No. 19,027 and No. 40,938; in Italy September 30, 1885, XIX, 18,629, and XXXVII, 153, and in Spain November 3, 1885, No. 7,724.

To all whom it may concern:

Be it known that I, FERDINAND BRUNBAUER, engineer, a subject of the Emperor of Austria-Hungary, residing at Vienna, in the Province 5 of Lower Austria, in the Empire of Austria-Hungary, have invented certain new and useful Improvements in Injectors; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 This invention relates to a new and useful improvement in injectors for feeding boilers; and it consists in the peculiar arrangement and construction of the parts, as hereinafter described, and pointed out in the claims.

20 The object of my invention is to construct an injector in such a manner that its starting and its internal parts are more simplified and its operation rendered more reliable. For this purpose the injector is provided with two 25 steam-tubes, one of them concentrically inclosing the other, the outer one of which tubes (whose passage, in consequence of the said arrangement, is of annular section, and which acts immediately after the opening of the boiler 30 steam-valve) operates the sucking in or setting in motion of the water, while by a subsequent adjustment of a starting-lever, or by other means, the movable inner tube is retired from a fixed conical valve, (until this moment

35 closing the latter,) whereby steam is permitted to also enter the inner or main steam-tube, by which the pressure and the velocity of the water are increased sufficiently to lift the check-valve of the boiler. In the second of 40 the two stages of the starting of the injector a starting-valve or stop-cock (through which the initial waste of water escapes from the outer shell or casing of the instrument) is closed by a system of cranks and links connected either to the starting-lever or to other 45 means for removing the inner tube.

To allow the two concentric steam-tubes to be operated in the aforesaid manner, I construct the inner or main steam-tube to be al- 50 ways movable in its axis for the purpose of re-

tiring the same from the fixed conical valve, while the outer steam-tube may either be made fixed or be movable, in which latter case it may be removed by the adjustment of the inner tube, or by any other means.

55

For the reliable operation of this injector it is necessary to construct the injector and the starting valve or cock in such a manner that in starting the instrument the steam and water may partly escape from the overflow-chamber and partly from the discharge-chamber. I am aware that there are other constructions of injectors for this purpose; but I have found it necessary that this double escape of the jet of condensed steam and water should be completely separated from each other in one and the same starting-valve.

65 Injectors embodying my invention are represented in the annexed drawings, as follows:

70 Figure 1 is a sectional elevation of an injector having the movable central steam-tube, a fixed outer tube, and the starting-lever in combination with the starting-valve. Fig. 2 represents in a similar elevation another construction of the starting-valve. Fig. 3 is a 75 sectional elevation of an injector similar to that shown by Fig. 1, but having both steam-tubes rigidly connected to each other. Fig. 4 is a sectional elevation of an injector, also similar to that shown in Fig. 1, but exclusively 80 arranged for upward action, and having its movable inner steam-tube adapted to be lifted by steam-pressure. Fig. 5 represents a modified part of Fig. 4.

85 In Fig. 1 the casing *a* of the injector communicates by its aperture *a'* with the pipe conveying the boiler-steam, and its aperture communicating with the boiler contains a valve, *a''*, kept closed by the boiler-pressure. The diaphragm between the steam-chamber 90 *a'* and the water-chamber *a''* has the fixed outer steam-tube, *b*, rigidly inserted in a corresponding opening. In the axis of said tube *b* the main steam-tube *c* is endwise movable. The central steam-tube, *c*, is guided at one 95 end in the widened portion of the outer tube, *b*, by means of its collar *c'*, having steam-passages *c''*, and at its other end is guided in a cylindrical opening, *h'*, of the screw-cap *h*. This screw-cap *h* contains a fixed screw-plug, 100

k, forming at one end a conical face or valve, by which the stroke of the steam-tube *c* is limited, as the corresponding end of said tube *c* is ground out like a valve-seat and enabled to be tightly forced onto the aforementioned conical face *k*.

For adjusting the main steam-tube *c* a crank-pin, *f'*, is provided, projecting from a short shaft, *f*, which extends into the casing *a* through a stuffing-box. The crank-pin *f'* engages with a guide, *c'*, formed on the steam-tube *c*. On its outer end the shaft *f* carries a hand-lever, *f''*, and by means of a crank, *f'''*, and a connecting-rod, *f''''*, said shaft is connected to a crank, *g'*, rigidly fitted on the plug *g''* of a starting-valve, which allows the exit of the water during the stage of drawing the water or setting it in motion. The casing *g* of said starting-valve is constructed in such a manner that during the starting of the injector a double completely separated escape of the mixture of condensed steam and water is provided. For this purpose the plug *g''*, forming on its bottom end a conical valve, *g'''*, is inserted in the top end of another valve, *g''''*, which valve is constructed like a tube with passage *g''''*, and forms a valve-seat, *g''''*, adapted to act in correspondence with valve *g'''''*.

The aforementioned conical valve *g'''''* acts in correspondence with a conical valve-seat, *g''''*, of the starting-valve casing *g*, and forms with said casing another passage, *g''''*, of ring-shaped section. In two diaphragms of the casing *a* are rigidly inserted the combining-tube *i* with the delivery-tube *j*, made in one piece, though an open space for overflow or relief is left between said tubes. During the starting of the injector the overflow-chamber *a''* communicates with the passage *g''''* of ring-shaped section, while the discharge-chamber *a'* is also in communication with passage *g'''''*. When the hand-lever *f''* is in the position shown by Fig. 1, the inner tube, *c*, is pressed against the conical face *k*, and the steam entering at *a'* is only permitted to issue through the steamway of ring-shaped cross-section formed between the outer steam-tube, *b*, and the inner steam-tube, *c*. In consequence thereof the drawing or the setting in motion of the water begins. The steam and water then enter the combining-tube *i*, formed integral with the delivery-tube *j*, and escapes into the atmosphere partly through the overflow-chamber *a''* and passage *g''''*, and partly through the discharge-chamber *a'* and passage *g'''''*. When the hand-lever is turned through an angle of about ninety degrees, the main steam-tube *c* is removed from the conical face *k*, and therefore steam is permitted to issue also through the inner tube, *c*, while at the same time the starting-valve is closed at *g'''''* and *g''''*. The double escape of the steam-and-water mixture therefore ceases, and the pressure or velocity of the jet of steam and water is raised sufficiently high so as to overcome the pressure in the boiler, so that the valve *a''* is forced down and the water fed into the boiler.

The starting-valve shown in Fig. 2 is constructed in a little different manner from that represented in Fig. 1; but the parts being peculiar to both constructions are indicated with similar letters. Here the plug *g''* of the starting-valve forms itself the two valves *g'''''* and *g''''*, and a diaphragm, *g''''*, is adapted to separate the two escapes *g'''''* and *g''''* from each other.

The injector shown by Fig. 3 is quite similar to that shown by Fig. 1, with the sole difference that both steam-tubes are rigidly connected together, and the outer tube, *b*, which is provided with a packing, *b'*, is movable in the aperture of the diaphragm between the steam-chamber *a''* and the water-chamber *a'*.

The use of the conical face *k* for keeping closed the main steam-tube *c* is of special advantage in injectors intended to force the liquid upward, like that shown by Fig. 4, which figure is to be turned ninety degrees, so that the pin *k'* is at the bottom end of the injector. In this modification the lower end of the inner steam-tube, *c*, rests from the action of gravity upon the fixed screw-plug *k*, and when the boiler-steam is allowed to enter through the aperture *a'* said steam contributes to tightly force the tube *c* onto the plug *k*. Afterward, when the pin *k'* is pressed inward, it strikes against the cross-pin or tappet *c'*, fixed within the tube *c*, and as soon as this tube is somewhat lifted the entering steam will fully lift it. The lifting of the tube *c* can, however, also be effected exclusively by the entering steam, as the impulse given to said tube by pin *k'* can be avoided by the modified construction shown by Fig. 5. *h* is here the screw-cap containing the afore-mentioned fixed conical plug *k*, which in this case is made with a hollow space having steam-inlet apertures *k''* and steam-outlet aperture *k'''*. The pin *k'* is formed with a conical end, which is enabled to close the outlet-aperture *k'''*. When the boiler-steam is allowed to enter the steam-chamber of the injector, the steam contributes, as in Fig. 4, to tightly force the tube *c* onto the plug *k*. Afterward, when the pin *k'* is a little unscrewed, a sufficient quantity of steam is permitted to enter the tube *c* and to lift it somewhat, and the larger quantity of steam now entering the tube *c* between the end of this tube and the conical face *k* will fully lift said tube *c*.

I claim—

1. In an injector with two concentric steam-tubes, the inner one of these tubes being endwise movable, forming between them a steamway of ring-shaped section, and adapted to operate a fixed cut-off valve by the movement of the inner tube, the combination, with said tubes, of a fixed conical valve for the inner tube, a valve-seat on the movable inner tube adapted to act in correspondence with said fixed conical valve, and means for the adjustment of the tube, substantially as and for the purpose set forth.

2. In an injector with two concentric steam-tubes, the inner one of these tubes being end-

wise movable, forming between them a steam-way of ring-shaped section, and adapted to operate a fixed cut-off valve by the movement of the inner tube, the combination, with said tubes 5 *b* and *c*, of a fixed conical valve, *k*, for the inner tube, *c*, a valve-seat on the movable inner tube, *c*, adapted to act in correspondence with said fixed conical valve *k*, and pin *k'*, for the purpose of shifting the tube *c* by steam-pressure, substantially as described.

3. In an injector with two concentric steam-tubes, the inner one of these tubes being end-wise movable, forming between them a steam-way of ring-shaped section, and adapted to 15 operate a fixed cut-off valve by the movement of the inner tube, the combination, with said

tubes, of a fixed conical valve for the inner tube, a valve-seat on the movable inner tube adapted to act in correspondence with said fixed conical valve, means for the adjustment 20 of the tube, and a starting-valve for double water-escape, containing a valve for closing the outlet from the overflow-chamber, and a second valve for closing the exit from the discharge-chamber, all connected and operating 25 substantially as described.

In testimony whereof I affix my signature in presence of two witnesses.

FERDINAND BRUNBAUER.
